United States Patent Office

Des. 187,715
Patented Apr. 19, 1960

187,715

CONTOUR-PROFILER MACHINE

Robert Louis Deschamps, River Forest, and Charles R. Onsrud, Niles, Ill., assignors to Onsrud Machine Works, Inc., Niles, Ill., a corporation of Illinois

Application October 16, 1959, Serial No. 57,956

Term of patent 14 years

(Cl. D54—14)

FIG. 1

FIG. 2

Des. 187,715

PAGE 2

FIG. 3

FIG. 4

FIG. 5

FIG. 6

Figure 1 is quarter-front perspective view of a contour profiler machine showing our new design.

Fig. 2 is a front elevational view of the same.

Fig. 3 is a top plan view of the same.

Fig. 4 is a rear elevational view of the same.

Fig. 5 is a left-hand end view of the same, and

Fig. 6 is a right-hand end view of the same.

We claim:

The ornamental design for a contour-profiler machine, as shown.
